United States Patent

Des. 236,559
Patented Sept. 2, 1975

236,559

SPORT SHOE

Jonas Senter, Greenwich, Conn., assignor to CITC
Industries, New York, N.Y.

Filed June 18, 1974, Ser. No. 480,535

Term of patent 14 years

Int. Cl. D2—04

U.S. Cl. D2—310

FIG. 1

FIG. 3

FIG. 2

FIG. 4

FIG. 5

FIG. 6

FIG. 1 is a front perspective view of a sport shoe showing my new design;

FIG. 2 is an enlarged side elevational view thereof;

FIG. 3 is a rear elevational view;

FIG. 4 is a top plan view;

FIG. 5 is a side elevational view of a second embodiment of the design of FIG. 1; and

FIG. 6 is a side elevational view of a third embodiment of the design.

I claim:

The ornamental design for a sport shoe, as shown and described.
